UNITED STATES PATENT OFFICE.

JOSEPH C. PRIMS, OF HORNELL, NEW YORK.

LEATHER-CUTTING MACHINE.

1,252,172.

Specification of Letters Patent.

Patented Jan. 1, 1918.

Application filed April 25, 1917. Serial No. 164,427.

To all whom it may concern:

Be it known that I, JOSEPH C. PRIMS, a citizen of the United States, residing at Hornell, in the county of Steuben and State of New York, have invented certain new and useful Improvements in Leather-Cutting Machines, of which the following is a specification.

The present invention relates to improvements in leather skiving machines, designed particularly for the purpose of cutting leather belts for splicing. The present invention is an improvement on the construction of leather skiving machines and involves certain combinations and arrangements of parts (whereby the skiving knife is submerged in the leather) before the cutting operation is initiated in order that a clear and straight edge will be made at the ends of the severed belt and eliminating the irregular edge usually resulting from the use of the knives now in use. The invention also involves the utilization of an abutment of comparatively soft material placed in the path of the knife edge at the end of the movement of the rotating platen or carrier. Certain other features will also be pointed out hereinafter in my specification and claims, whereby a practical, facile, and efficient skiving machine is provided for performing the required functions.

In the accompanying drawings I have illustrated one complete example of the physical embodiment of my invention constructed according to the best mode I have so far devised for the practical application of the principles of my invention.

Figure 1 is a front elevation of a skiving machine embodying the novel features of my invention, the front plate of the machine being omitted for convenience of illustration.

Fig. 2 is a transverse sectional view on line 2, 2 of Fig. 1, the front plate being present.

Fig. 3 is a view similar to Fig. 1, but here the rotating carrier has been turned and the leather belt cut, the carrier being now at the terminus of its movement and ready to be returned to normal position.

Fig. 4 is a top plan view of the machine as in Fig. 1.

Fig. 5 is a longitudinal section through the knife-holder.

55 In the preferred embodiment of my invention as illustrated in the drawings and

as now actually in use, the supporting frame 1, preferably in the form of a circular disk is fashioned with the bracket arm 2 and lugs 3, 3, the boss 4 being threaded for the clamping hand screw 5 by means of which the machine may be attached to a bench or other support indicated as 6.

At its upper end the frame is mortised to receive the horizontally disposed housing or holder 7 for the knife 8, it being understood that the knife is stationary and the leather belt or other "work" is moved to the cutting edge of the knife during the process of skiving or paring. To this end the holder is rigidly secured in the frame by the bolt 9 passed through the perforation 10 in the holder and threaded into the frame. The holder is slotted at 11 to receive the knife blade and the cutting edge projects from the holder so that it may engage the leather belt as indicated by the numeral 12. The slot 11 is of sufficient size so that the knife blade may be moved longitudinally of the holder, and to this end a pair of aligned fixed pins 13 and 14 are provided in the holder and the slots 15, 15 in the blade move about these pins as the blade is shifted endwise. To shift the blade I employ a lever handle 16 fulcrumed on the fixed pin 17 and movable in the slot 18 in the rear edge of the holder, and the opposite end of the lever is rounded at 19 to work in the rounded recess 20 at the back edge of the knife blade. Thus when the lever is turned on its fulcrum the blade may be shifted longitudinally in its holder.

As before stated, the knife is stationary and the belt is brought to the knife by a rotating carrier, which is revolvably supported in the long hub or bearing sleeve 21 of the frame 1. The sleeve is located centrally of the frame and the carrier 22 is fashioned with a central hollow, or tubular shaft 23, rotatable in the bearing sleeve or hub, and the carrier is actuated through the medium of the actuating lever 24 keyed at 25 to the hollow shaft, and retained by the end washer 26 secured by the bolt 27 in a bearing 28 at the outer end of the hollow shaft. A long bearing is thus provided, for the movement of the carrier and its movement is consequently steadied and rendered accurate.

The periphery of the carrier as indicated at 28^a is smoothed and finished in order to provide a knife bearing surface, and the

carrier which is fashioned as a circular disk, corresponds in outline to the circular disk of the frame 1. In operation the knife is made to cut on a tangential line into the leather belt, and this tangential cut is accomplished by the utilization of an eccentric member or platen 29. This platen 29 is a broad circular plate, of a little less diameter than the disk of the carrier and particularly the 5 knife bearing surface 28^a, and is pivoted on the carrier by means of the hinge pin 30 which passes through the bearing sleeve 31 of the plate. At the end of the plate opposite the hinge, a spring 32 is attached and 10 the other end of this spring is fixed to a lug or flange 33 extending the full width of the platen and projected from the carrier 22.

At the central portion of the underside of the platen is a circumferentially extending 20 integral rib 34 provided with a finished face 35 and terminating in a stop lug 36. In frictional contact with this surface at all times is the head 37 on the short arm 38 of the eccentric lever 39 which is formed with 25 a bearing sleeve 40 that is rotatable on the stud 41. This stud is an extension of the hollow shaft 23, but it will readily be seen that the stud is eccentrically disposed with relation to the center of the shaft, that is the 30 axis of the stud is off center with relation to the axis of the tubular shaft, and this arrangement of parts permits of a movement of the platen 29 so that the periphery of the platen may have its position changed with 35 relation to the true circle in order that as the carrier or platen is turned, the knife edge is forced through the leather on a tangential line.

While being cut the leather belt is held 40 to the carrier by means of a cam lug 42 extending the full length of the sleeve 43 having a bearing on the stud or bolt 44 projecting from the carrier, and this cam lug may be turned by the cam lever 45 to clamp the 45 belt on the plate 46. At the other side of the cutting knife the belt may be held down on the platen as it passes under a pressure roller 47 supported in a housing 48 which is pivoted by means of the sleeve 49 on the 50 stud or bolt 56, a handle 51 being provided for operating the pressure roll. By means of the cam 42 the leather belt is clamped on the carrier and the clamp or cam holds the leather belt by frictional contact therewith, 55 but the pressure roller is held down on the belt by hand, as the belt passes under the roller. In Fig. 1 it will be noted that the roller is located just in front of the knife edge, and it will be seen that a wooden or 60 fiber strip 52 is secured in a groove extending across the platen at its hinged end and projects up above the surface of the platen. This strip of soft material, in addition to 65 performing the function of an abutment for the knife edge, raises the material of the

belt so that the knife edge will pass through the underside of the belt leaving a clear straight edge to the cut. The carrier is provided with a front plate 53 secured by a screw or bolt 54 to the stud 41 of the carrier shaft, and on the flange 55 of the plate, a scale is indicated for use in cutting the belts. The belt is then inserted, preferably under the cam 42, and moved under the knife and roller to position on the platen 70 so that the end of the belt is resting on the abutment 52 which is the highest point of the platen and the point where the final cut of the knife is made, and then the belt is clamped by the cam 42. The carrier is now 75 turned to the right in Fig. 1 to a position so that the length of the desired cut will be the distance between the knife edge and the abutment 52. The handle or lever 39^a is now turned to elevate the eccentric platen, 80 the head 37 riding under the rib 34 and lifting the hinged platen which presses the belt firmly up against the knife edge, so that the knife edge depresses the surface of the belt, and when the handle 16 is moved to 85 shift the knife longitudinally, the knife cuts into the belt, making a sharp, straight and clean initial cut. With the leather now held down on the platen by the lever 51 through its roller 47 the lever 24 is turned 90 to the right in Fig. 1 and the knife edge cuts through the leather from top to bottom as the belt is forced past the knife, the result being that a tapered end is provided 95 for the belt to be spliced and when both ends 100 have been cut to form a taper lap the lapped ends may be cemented or glued together as usual. The knife bearing surface 28^a of the carrier passing under the knife edge prevents the knife from being forced down to 105 the platen as the belt passes over the knife, and the pressure roller 47 holds the belt down on the platen as the belt passes under the roller. Due to the fact that the initial 110 cut of the knife edge into the material is accomplished before the actual skiving operation is started, and also to the fact that the end of the belt is lifted so that the knife edge will cut clear through the under side of the belt, an improved form of overlapping splice ends is provided. When the two beveled faces of the belt ends are brought together and cemented or glued, the ends or edges of the beveled overlapping pieces fit snugly into the recesses cut by the knife edge 115 at its initial movement, and a smooth face on both sides of the belt is presented.

In my former patent referred to herein, the knife or cutter was secured to remain fixed or stationary under all conditions, 125 while in the present invention the knife is stationary with reference to the direction of the feed of the work, but is capable of a sliding motion in a direction transverse to the direction of the feed of the work, which 130

is a very great improvement and a most important difference, as this construction enables the knife to be submerged in the leather and under these conditions to be moved sidewise or transversely which gives the leather a clean shear cut.

What I claim is:—

1. The combination with a supporting frame and a stationary knife of a work carrier rotatably supported in the frame and adapted to present the work to the knife edge, and an abutment carried by the carrier and composed of comparatively soft material to engage the knife edge at the end of 15 the carrier movement.

2. The combination with a rotatable carrier and a fixed knife, of a platen hinged on the carrier, means for moving said platen to permit a beveled cut to be produced by 20 the knife in the leather to be treated, and an abutment of soft material for the knife attached to the platen at its point of hinging.

3. The combination with a supporting frame and fixed knife, of a carrier adapted to support a leather belt, means for moving the belt to position to permit an elongated bevel cut to be produced therein by the knife, and means for submerging the edge of the 30 knife in the belt prior to the cutting operation of the knife.

4. The combination with a supporting frame and a fixed knife, of a carrier adapted to support a leather belt, means for moving 35 the belt to position to permit an elongated

bevel cut to be produced therein by the knife, means for submerging the knife edge in the belt prior to the cutting operation, and means for positioning the end of the belt so that the knife edge will take a course more 40 nearly perpendicular through the body of the belt as it emerges therefrom.

5. The combination of a fixed knife, a rotatable carrier, a movably-mounted platen, means for moving the same to permit a beveled 45 cut to be produced by the knife in the belt, and means for causing the knife edge to take a course nearly perpendicularly through the body of the belt as it emerges therefrom. 50

6. In a leather cutting machine, the combination of a stationary support, a movable platen, a knife mounted above said platen fixed longitudinally with reference to said platen, and means for manually moving said 55 knife transversely to start the knife in the leather.

7. In a leather cutting machine, the combination of a fixed support, a rotatable carrier, a movable platen, means for moving 60 said platen, and a knife having a fixed longitudinal relation to said platen and capable of a transverse movement to start the knife in the leather.

In testimony whereof I affix my signature 65 in the presence of two witnesses.
